[57] CLAIM

The ornamental design for a clamping strap for electrical wires, as shown and described.

DESCRIPTION

FIG. 1 is a perspective view of a clamping strap for electrical wires showing our new design, the broken lines indicating that the configuration of the strap repeats uniformly along its length;

FIG. 2 is a front view thereof;

FIG. 3 is a right view thereof;

FIG. 4 is a top view thereof;

FIG. 5 is a bottom view thereof;

FIG. 6 is a rear view thereof;

FIG. 7 is a sectional view taken in the direction of the arrows on line 7—7 of FIG. 2;

FIG. 8 is a sectional view taken in the direction of the arrows on line 8—8 of FIG. 3;

FIG. 9 is a perspective view thereof in its position of use, the bundle of wires being shown in broken lines for illustrative purposes only.

FIG. 9
